Attorney

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,296,490.

Specification of Letters Patent.

Patented Mar. 4, 1919.

Application filed October 15, 1918. Serial No. 258,172.

To all whom it may concern:

Be it known that I, FRANK DUTCHER, a citizen of the United States, residing at Versailles, in the county of Allegheny and State of Pennsylvania, have invented certain new and useful Improvements in Railway Signal-Torpedoes, of which the following is a specification, reference being had therein to the accompanying drawing.

10 This invention relates to improvements in railway signal torpedoes, and is of the paper or fibrous case type of torpedo in which the inclosing case is of a cup-shaped form.

The type of torpedo upon which my present invention is an improvement, has the edge of the side peripheral wall of the cup-shaped inclosing case crimped inward to lock the case containing member within the outer case, the crimped in portion being substantially parallel with the side wall of the cup-shaped member.

In order to make this type of torpedo water-proof, the crimped edge is forced tightly against the explosive retaining member, and it is essential that the crimp should remain in its tight compressed position. The crimp of paper used in torpedoes does not have very much body, and it has a tendency to loosen up in the presence of moisture, due to the weather exposure to which such torpedoes are necessarily subjected.

One object of my invention is to so construct and arrange the parts of this type of torpedo, that the crimped in edge of the inclosing case is locked against any loosening up under the influence of moisture or otherwise, so that a tight clamping action is always insured.

Another object of my present invention is to have the member for locking the crimped portion perform the additional function of fastening the rail-embracing strap to the torpedo for holding it on the tread of the railroad rail.

Another object of my present invention is to have the outer holding wall for the explosive tablet, consist of a disk which is locked in position by the crimped in edge of the inclosing case.

Another object of my invention pertains to the detailed arrangement and construction of the several parts, comprising the case for holding the explosive tablet, which

will be pointed out hereinafter in the description thereof. 55

In the accompanying drawings—
Figure 1 is a top perspective view of a torpedo embodying my invention, showing it held on top of a railroad rail. 60

Fig. 2 is a vertical transverse sectional view of Fig. 1.

Fig. 3 is a vertical central transverse sectional view of my improved torpedo, showing a slight modification in the construction 65 of the combined crimped locking member and holder for the rail-engaging strap.

Fig. 4 is a vertical central sectional view of the parts comprising the torpedo, they being shown in separated relation, and the 70 rail-engaging strap omitted.

Fig. 5 is a plan view of the combined crimp locking and strap-carrying member, shown in Figs. 1, 2 and 4.

Fig. 6 is a plan view of the combined 75 crimp locking and strap carrying member shown in Fig. 3.

Fig. 7 is a top plan view of a torpedo involving the broad principles of the invention, but showing a modification thereof. 80

Fig. 8 is a vertical central transverse sectional view of Fig. 7.

Fig. 9 is a central vertical sectional view of the modified construction, showing the parts in separated relation. 85

Referring now to Figs. 1, 2, 4 and 5, 1 is a cup-shaped paper or fibrous member in which a second cup-shaped fibrous member 2 is placed, arranged with its open face corresponding to the open face of the member 1. Placed within the member 2 is an explosive tablet 3.

The cup-shaped member 1 is an outer or inclosing cup-shaped case, and the member 2 is an inner explosive carrying cup-shaped 95 case, which is much shallower than the cup-shaped member 1. That is to say, when the inner case 2 is placed within the outer case 1, as shown in Figs. 1, 2 and 3, the side wall or flange 4 projects considerably beyond the side wall or flange 5 of the inner cup-shaped case 2. As shown, the explosive tablet 3 is of a thickness corresponding to the inner depth of the inner case 2. A paper disk 6 fits snugly within the outer 100 case 1, and rests upon the edge 5 of the inner case 2, and upon the explosive, as shown. When the parts are in this posi-

tion, the edge of the outer case flange 4 is crimped inward in a position substantially parallel to the wall of the flange 4, as shown at 7, and is crimped tightly against the disk 6, for locking it tightly against the edge of the flange 5 of the inner case 2. Preferably, the explosive tablet 3 is a trifle thinner than the width of the flange 5, so that the disk 6 will be locked tightly against the flange 5, by the crimped portion 7. With the flange of the inner case projecting downward, as shown, the inner extending portion of the U-shaped crimp 7 is substantially in line with the edge of the flange 5 of the inner case, which is one of the improved arrangements of parts involved in my present construction.

Another feature of my present improvement is the provision of means for locking the U-shaped crimp 7 in its tightly clamped position, to prevent any loosening up or releasing of the clamping action. This improvement consists in providing an outer disk 8, which is placed against the inner disk 6 and cemented thereto, and is of a diameter to tightly fit against the inner wall of the crimped portion 7, thus holding or locking the crimped portion in its tightly crimped position and preventing it from loosening or releasing under the action of the moisture or otherwise. In fact, the diameter of the locking disk 8 is preferably such as to force the inner wall of the crimped portion 7 outward, so that if the crimped portion has any tendency to loosen after being crimped, it is forced to its tight clamping or crimping action by the locking disk 8.

This locking disk 8 is also utilized to secure the rail clamping strap 9 to the torpedo. In the form shown in Figs. 1, 2, 4 and 5, the locking disk 8 is provided with slots 10, through which the rail strap 9 is threaded.

In Fig. 3, I show a modification in the construction of the locking member 9, in that a locking member 9^a of disk form is provided, and this locking member is provided at opposite edges with notches 11, through which the rail engaging strap 9 is threaded, as shown in Fig. 3. The locking disk 9^a is made of a diameter to act upon the U-shaped crimp 7 in the same manner as the locking disk 8 and is cemented to the inner explosive holding disk 6, the same as in Figs. 1 and 2.

In Figs. 7, 8 and 9, I show a modification in that the inner case 2 is omitted. In this modified form the outer case 1^a has its flange 5^a with its edge 7^a crimped inward, as in the form shown in Figs. 2 and 3, against an explosive retaining disk 6^a, which fits snugly within the inclosing case 1^a. In this construction I utilize my improved locking device for the crimped portion and it consists of a disk 8^a constructed like the locking disk of Fig. 2, and it acts to lock

the crimped portion exactly as in Figs. 2 and 3, and has the rail-engaging strap 9^a threaded through it as in Fig. 2, though it will be understood that the locking disk form shown in Fig. 6 may be used as well and substituted therefor.

Attention is directed to the fact that the locking disk in these several forms is made of a thickness approximately equal to the depth of the crimp of the outer case, for the purpose of filling in the space and making the torpedo level on its lower face as well as its upper face, with the exception of the slight bulge occasioned by the threading of the strap.

The torpedo may be made water-proof in any of the well known ways by using the usual water-proof paper and dipped into suitable water-proof compound, or by using paper which is not water-proof, and then after the torpedo is completed, dipping it into a suitable water-proofing compound, which will be absorbed by the paper, but this forms no part of my present invention.

Having thus described my invention, what I claim and desire to secure by Letters Patent is—

1. An improved railway signal torpedo, comprising an outer inverted case, an explosive therein, a disk within the case, the side wall of the case projecting beyond the disk and crimped inwardly tightly against it forming a recess at the bottom of the case, and a locking disk fitting within the recess and holding the crimped portion against loosening.

2. An improved railway signal torpedo, comprising an explosive containing case, an explosive therein, a disk within the case outside of the explosive, the flange of the case projecting beyond the disk and crimped inward tightly against it forming a recess at the bottom of the case, and a locking disk outside of the first said disk and cemented thereto and having its periphery engaging and locking the crimped portion of the case in its tightly crimped position.

3. An improved railway signal torpedo, comprising an explosive holding case, an explosive therein, a holding member within the case and outside of the explosive, the flange of the case projecting beyond the holding member and clamped tightly inward against the holding member thus forming a recess at the bottom of the case a locking disk outside of the holding member and having its periphery engaging the crimped portion of the case, for the purpose described, and means holding the locking disk in position.

4. An improved railway signal torpedo, comprising a cup-shaped case, a shallower cup-shaped case within the first said case, an explosive within the inner case, a disk within the first said case and engaging the edge

of the inner case, the side wall of the first said case projecting beyond the disk and crimped inward tightly against it, and a locking disk outside of the first said disk and of a diameter to hold the crimped in portion against spreading or loosening its clamping action, and a rail-engaging strap.

5. An improved railway signal torpedo, comprising an outer explosive containing case, an explosive therein, an explosive holding member within the case, the side wall of the case projecting beyond the said holding

member and crimped inward tightly against the holding member forming a recess, and a locking disk within the recess and engaging the inwardly crimped portion, for the purpose described.

In testimony whereof I hereunto affix my signature in the presence of two witnesses.

FRANK DUTCHER.
